FACSIMILE PRINTING TELEGRAPH
RECEIVER

Edward F. Kleinschmidt, Highland Park, Ill., assignor to Teletype Corporation, Chicago, Ill., a corporation of Delaware

Application February 19, 1934, Serial No. 711,862

23 Claims. (Cl. 178—11)

This invention pertains to printing telegraph machines and more particularly to facsimile telegraph systems and apparatus.

The present invention relates more specifically to facsimile telegraph systems and apparatus in which letters and other characters are transmitted character by character to form a directly legible printed line, and in which successive characters occupy approximately equal lineal units of space in the line. In such systems, start-stop mechanisms may be employed in which a printing mechanism is started by a signal over the line, is operated to record one character, and then is stopped by means local to the receiver or by means controlled by a special signal over the line. Such systems necessarily require all moving parts to be of light construction so that they may be started quickly and stopped easily.

20 An object of the present invention therefore is to provide a simple, efficient, and reliable facsimile printing telegraph apparatus wherein special control or synchronizing impulses are not required.

25 A further object is to provide a facsimile printer with means for starting and stopping the recording tape in response to the character signals.

The above and further objects are attained by 30 providing a start-stop mechanism for controlling the recording tape of the facsimile receiver and permitting all other locally driven members to operate continuously. In such operation by the device shown herein, the location of a printed 35 character may vary in position upon the record tape, being above or below the true middle of the tape, but with the provision of a double number of printing edges on the printing wheel, the equivalent of two images of each character is 40 produced upon the recording tape for every character transmitted, and one of these two images always will be integrally located upon the recording tape, the other being either integral or divided into two parts respectively above and 45 below the one integral image.

Spaces between words are provided in one species of apparatus by sending a dash signal for the purpose of starting the tape, while in another species of apparatus the recording tape is 50 permitted to run between words for a limited time without control of line signals, thereby producing a blank interval of recording tape during a cessation of character signals.

A better understanding of the invention may 55 be had from the following description, taken in

conjunction with the accompanying drawing, wherein

Fig. 1 shows a plan view of a facsimile receiving printer according to this invention;

Fig. 2 shows a front elevation of the structure 5 shown in Fig. 1;

Fig. 3 shows an alternative method of releasing the tape driving mechanism and shows also a line circuit and transmitter;

Fig. 4 shows in plan, an alternative design for 10 driving the tape;

Fig. 5 shows a front elevation of those essential elements of Fig. 4 which are different from the structure of Fig. 1, and

Fig. 6 shows a sample of a record produced 15 by the species of Fig. 1.

In Figs. 1 and 2, a motor 1 drives a printing shaft 2, and through reducing gears 3, with a ratio of about 6-to-1, and through friction clutch 4 drives also the start-stop tape shaft 5, shown 20 also in Fig. 3. Shaft 5 carries driving roller 6 which cooperates with presser roller mechanism 7 and carries also stop cam 8 having four stop notches 9, any one of which may be engaged by stop pawl 10 on rock shaft 11 which is rocked by 25 finger 12 under control of armature 13.

The magnetic system of the receiver comprises a core 20 with return pole pieces 21 and polarizing winding 22 energized by battery 23 in circuit 24, cooperating with armature 13, which comprises a 30 member of insulating material having an annular groove which contains a winding 25 connected by flexible wires to terminals 26 and 27, the armature 13 being mounted upon a flat spring 28 which has a normal tendency to lift the armature 13 away from the core 20. The armature 13 carries a knife edge 30 which, when the armature retires from core 20, engages the recording tape 31 to press it and ink ribbon 32 against the fluted printing wheel 33 on shaft 2. In Figs. 40 2 and 3, the armature 13 is shown in attracted position, representing that current is flowing through winding 25 in such direction as to cooperate with current through winding 22 to produce an attraction of armature 13, thereby holding knife edge 30 out of engagement with tape 31 and wheel 33.

In Fig. 3 is shown a line wire 35 and a transmitter 36 comprising a code wheel 37, a transmitting brush 38, a start-stop cam 39, and a 50 character key 40 controlling a circuit comprising battery 41, resistor 42, code wheel 37, brush 38, and relay 43.

The operation of the species shown in Figs. 1 and 2 in cooperation with the keyboard trans-

mitter 36 is as follows: Normal current is from negative source through contact of deenergized relay 43, wire 35, and winding 25 to ground 44. Under such conditions, armature 13 will be held against core 20. Operation of key 40 releases code wheel 37 to start and to make one revolution, during which revolution a set of code impulses is delivered from battery 41 to relay 43 which responds to the impulses individually and delivers 10 to line wire 35 a corresponding code of impulses from positive source of energy alternating with impulses from the normal or negative source of energy. Upon receipt of the first signal printing impulse, armature 13, Fig. 2, rises and effects two 15 results; first, that it lifts finger 12, rocks shaft 11, and lifts pawl 10 from notch 9 of stop cam 8, thereby permitting shaft 5 and roller 6 to drive tape 31, and second, that it lifts knife edge 30 on armature 13 to engage tape 31 and to press it 20 against printing wheel 33 so that the movement of the spiral knife edges of fluted printing wheel 33 cooperate with knife edge 30 of armature 13 to cause ribbon 32 to mark upon recording tape 31. Because of the number and arrangement of 25 spiral edges on wheel 33, Fig. 1, and the length of knife edge 30, the result upon record tape 31 will be as shown on tape 45, Fig. 6, in which usually one complete character and two fractional characters will be printed in response to each character code of received line signals, and in which at times, two complete characters one above the other will be printed, but in which at all times at least one complete character will be printed in response to a character code of received signals. 30 At the end of one revolution of code wheel 37, its stop cam 39 will engage the stop dog 46 of character key 40, the code wheel 37 will stop, and the current on the line 35 will be of a polarity to energize coil 25 and retract knife edge 30. At about 35 the same time, a stop notch 9 of stop cam 8, Fig. 2, will be in alignment with pawl 10 and since finger 12 is not lifted, for coil 25 will be energized to retract its armature 13, the shaft 5 will be stopped, thus stopping tape 31. This completes the transmission of one character and the condition after completion is as follows: Relay 43 is deenergized, negative source at relay 43 is connected to line wire 35 which produces in winding 25, Fig. 2, an energization to hold armature 13 against core 20 and to remove knife edge 30 from tape 31 and printing wheel 33. Tape 31 is at rest because notch 9 on cam disc 8 has engaged pawl 10, but the printing wheel 33 driven by motor 1 continues to revolve. Tape 31 now is in position to receive a record of the next transmitted character code in location adjacent to the prior record, and this independently of the length of time elapsing between successive codes. During the vibration of armature 13 in response to the many 45 impulses of the code signal, the start finger 12 has been retained lifted from the armature 13 by the circular edge of cam disc 8, which lifts pawl 10 and rocks shaft 11 to hold finger 12 above and out of range of the movement of armature 13. 50 In Fig. 3, an alternative means for controlling the starting of cam disc 8 is shown. A pair of electrical contact points 50 is provided, one of which is attached to the core 20 and therefore to the wire 51, and the other of which is attached 55 to spring 28 and therefore to wire 52, the circuit being completed through battery 53 and magnet 54 which controls armature 55. In normal condition with armature 13 attracted toward core 20, the contact pair 50 will be closed, thereby energizing magnet 54 and causing the attraction of

armature 55 which introduces its hook end into a notch 9 of cam disc 8 and holds shaft 5 stopped, and therefore holds tape 31 stopped. Spring 56 tends to retract armature 55 to release disc 8.

The operation of the species shown in Fig. 3 is as follows: With magnet 54 normally energized, armature 55 normally attracted, and disc 8, shaft 5, and tape 31 normally stopped, the first impulse received from transmitter 36 over line 35 will cause armature 13 to rise for the purpose of printing, and this will open the contacts of the pair 50 which will deenergize magnet 54, releasing armature 55 to be retracted by spring 56, thus releasing disc 8 and permitting tape 31 to start. During the several signals of the ensuing code, the relay 54 will be energized repeatedly without effect until at the conclusion of the code the return to normal line current from negative source over line 35 will hold contact pair 50 closed and will hold magnet 54 energized so that armature 55 will be drawn into the next notch 9 of cam disc 8 to stop the tape 31. The advantage of this species over the species of Fig. 1 is found in the fact that at no time is any energy expended by armature 13 to start and stop the tape beyond the quantity of energy required over the line 35 to operate the knife-edge 30 to print.

No provision is made for starting the movement of the recording tape other than by response to a printing signal received over the transmission channel, hence no special provision is made for starting the tape without printing, as would seem desirable for producing a space between words. To separate the words of a message and yet to maintain the facsimile receiver in simplest form, a dash, as 46 on tape 45, Fig. 6, is used as a word space and serves to separate the words of a message while at the same time its printing signals in the line channel serve to start the tape after the end of each word, thus separating the successive words and supplying a mark upon the tape to emphasize the separation.

A further species of tape stop is shown in Figs. 4 and 5. There is provided a magnet 60 having an armature 61 to operate a rock shaft 62 against tension of spring 63. The rock shaft 62 carries a face plate 64 upon which are mounted arm 65, stop pin 66, and spring 67, the arm 65 being pivoted to plate 64 and spring 67 acting to urge the arm 65 against stop 68. Arm 65 projects to shaft 5 and has a screw-follower pin 69 which engages a screw thread 70 on shaft 5 and has further a striker finger 70 adapted to engage a stop pin 71 in disc 72 on the start-stop tape shaft 5.

The operation of the species shown in Figs. 4 and 5 is as follows: Magnet 60 is connected in a manner similar to magnet 54 in Fig. 3, being in circuit with wires 51, 52 and controlled by contact pair 50. The printing operations are as in Figs. 1 and 2. The tape stop and start operations are as follows: The first printing impulse deenergizes magnet 60 which releases armature 61 which rocks the shaft 62 which tilts the face plate 64, Fig. 5, and lifts arm 65 and pin 66 out of screw 69, thus permitting spring 67, Fig. 4, to operate arm 65 against stop 68, thus withdrawing striker finger 70 from the path of pin 71 and releasing disc 72 and shaft 5 to turn to drive roller 6 and thereby to drive the recording tape. The several marking impulses of the code combination now being received will deenergize magnet 60 repeatedly, but after the end of the character code the magnet 60 will remain energized, its armature 61 will remain attracted, pin 69 will

remain in screw thread 69, and by the action of the screw thread 69 upon the pin 68, the arm 65 will be moved and the striker 70 will be positioned in the path of stop pin 71 so that the shaft 5 will be arrested after an interval in which the tape will have been driven for a distance equivalent to two or three or more characters depending upon the pitch of the screw 69 and the setting of the adjustable stop 66, the former of which 10 is at the discretion of the manufacturer and the latter of which is at the discretion of the operator. With the tape controlling system of the species shown in Figs. 4 and 5 and with the transmitter shown in Fig. 3 operated skillfully, there 15 will be no stoppage of tape between successive characters and a uniform printing upon the tape will secured. This system is adapted particularly to transmission by control of perforated record forms wherein the transmission has extreme uniformity in the feature of time intervals. In lieu 20 of signals for a space between words, a time interval of one character is permitted, but no marking signal is sent thereby permitting the tape to be driven for a distance to provide for the space 25 between words after which the first letter of the next word will operate the magnet 60 to restore arm 65 out of the screw thread and against its stop 66 where it may be maintained by successive marking signals until another interval is permitted 30 for spacing, which interval may be extended slightly and then will become a stop condition for stopping the tape by engagement of member 70 with stop pin 71.

For a more complete description of the facsimile printing telegraph system, reference should be made to Patents 2,046,328 and 2,000,083 of July 7, 1936 and May 7, 1935, respectively.

The facsimile receiving apparatus herein described provides a receiving device of utmost simplicity in that the printing devices themselves are not subjected to starting and stopping nor to start-stop conditions of any kind and are of the simplest and strongest construction with a view to low cost and minimum maintenance. Further, 45 in the species of Figs. 4 and 5, there is no start-stop effect of any kind upon any operating member and a smooth and silent operation is attained.

From the previous description it is apparent that the features of the invention are to permit 50 the heavy parts of the receiver to operate continuously and not to subject the heavy parts to starting and stopping action, to start the recording tape by the first character signal impulse of line current which impulse also effects printing 55 upon the tape, to stop the tape after a travel equal to one printed character, using a special character or dash character to indicate a space between words, or alternatively to stop the tape after a travel equal to two or more printed characters 60 so that mere absence of printing signals will permit blank tape to pass the printing point and thus produce the effect of a space between words by the expedient of omitting signals for the time of transmission of one character to indicate a blank space.

The invention which has been described has many further applications and is not intended to be limited in scope by the specific embodiments shown herein for illustration.

70 The invention claimed is:

1. In a facsimile telegraph system, a printing wheel and a printing armature for facsimileing letter by letter upon a record tape by control of received code combinations of marking and spacing signals, a friction drive for moving the record

tape at a uniform speed, and a stop pawl for said drive for insuring the movement of the tape through a uniform distance for each character operation, said printing armature being operated to print and said stop pawl being operated to initiate said friction drive both by the first signal of a received code combination of marking and spacing signals.

2. In a facsimile telegraph system, a rotary mechanical printing means for facsimileing 10 character by character upon a record tape by control of received combinations of marking signals, and other means for moving the record tape, said printing means and said other means both being set in operation by the first message 15 character line signal of marking nature received.

3. In a facsimile telegraph system, a continuously rotating printing wheel and a printing armature for facsimileing upon a record tape and operating invariably to print in response to a 20 received marking signal, and tape control means controlled by said armature in response to received marking signals for advancing the tape.

4. In a facsimile telegraph system, means for transmitting marking signals in code groups, an 25 armature and a printing wheel for facsimileing upon a record tape in response to said marking signals, a friction drive for said tape, a tape stop device, and a circuit including said tape stop device and said armature and controlled by said 30 marking signals and adapted to release said friction drive to advance the tape in response to a facsimileing marking signal.

5. In a facsimile telegraph system, means for transmitting marking signals in code groups, a 35 printing wheel, an armature having a presser plate cooperating with said printing wheel for facsimileing upon a record tape in response to said marking signals, driving means for said tape, and a controlling circuit held closed in response to 40 spacing signals and opened in response to marking signals for setting in operation said tape driving means in response to a message character facsimileing marking signal.

6. In a facsimile telegraph system, means for 45 transmitting marking signals in code groups representative of message matter, rotary mechanical marking means for facsimileing upon a record tape the message matter in response to said marking signals, and tape controlling means also responsive to one of the marking signals in a group 50 for said message matter and adapted to move said tape in response thereto.

7. In a facsimile telegraph system, a continuously operating printing wheel, an armature operating to print in response to received marking signals and operating in response to spacing signals to restrain the printing elements from printing, a tape driving clutch, and a tape restraining pawl, said tape restraining pawl operating in response to a spacing signal to hold said clutch inoperative, and operating further in response to a printing signal to render said clutch operative.

8. In a facsimile telegraph system, a line circuit, a magnet having an operating winding included in the line circuit, an armature marking member moved directly by said operating winding to mark in facsimile manner upon a record tape, an electrical contact closed by said armature member when in spacing position, and a tape stop controlled by said contact.

9. In a facsimile telegraph system, a line circuit, a magnet having an operating winding included in the line circuit, an armature marking

member moved directly by said operating winding to mark in facsimile manner upon a record tape, a clutch for driving said tape, and an electrical contact controlling said clutch and closed 5 by said armature member when in spacing position.

10. In a facsimile telegraph system, a line circuit, a magnet having an operating winding included in the line circuit, an armature marking member moved directly by said operating winding to mark in facsimile manner upon a record tape, a clutch for driving said tape, a latch for controlling said clutch, and an electrical contact controlling said latch and closed by said armature 10 member when in spacing position.

11. In a telegraph system, a rotary mechanical facsimileing printing device, a member co-operating with said printing device for effecting printing of characters on a record medium, mechanism for advancing the record medium during the printing of each character, and means responsive to a received signal condition effective in the printing of a character for initiating the operation of said mechanism to advance the medium, after which the mechanism operates independently of signal conditions during the printing of 15 said character.

12. In a telegraph system, a rotary mechanical facsimileing printing device, a member co-operating with said printing device for effecting printing of characters on a record medium, power driven mechanism for advancing said record medium during printing of each character, and means responsive to a received signal condition 20 effective in the printing of a character for releasing said mechanism to advance the medium and thereafter said mechanism operates independently of signal conditions during the printing of said character.

13. In a telegraph system, a rotary mechanical facsimileing printing device, a member co-operating with said printing device for effecting printing of characters on a record medium, mechanism for advancing the record medium during the printing of each character, means responsive to a received signal condition effective in the printing of a character for initiating the operation of said mechanism to advance the medium, after which the mechanism operates independently of 25 the signal condition, and means for determining the period of independent operation of said mechanism.

14. In a telegraph system, a rotary mechanical facsimileing printing device, a member co-operating with said printing device for effecting printing of characters on a record medium, means for advancing said record medium during the printing of each character, means responsive to a received signal condition effective in the printing of a 30 character for initiating the operation of said mechanism, and means included in the medium advancing means operated initially by said signal responsive means and thereafter independently thereof for having said mechanism advance said medium a predetermined distance.

15. In a telegraph system, a rotary mechanical facsimileing printing device, a member co-operating with said printing device for effecting printing of characters on a record medium, means for advancing said record medium during the printing of each character, means responsive to a received signal condition effective in the printing of a character for initiating the operation of said means, and means including a friction drive con- 35

trolled by said means and thereafter effective independently thereof for a predetermined period for causing said advancing means to advance said medium.

16. In a telegraph system, a rotary mechanical facsimileing printing device, a member co-operating with said printing device for effecting printing of characters on a record medium, means for advancing said record medium during the printing of each character, means responsive to a received signal condition effective in the printing of a character for initiating the operation of said mechanism, means including a friction drive controlled by said means and thereafter effective independently thereof for a predetermined period for causing said means to advance said medium, and means effective after said predetermined period for disabling said friction drive and discontinuing the advancement of the medium.

17. A method of operating a facsimile telegraph system which comprises, sending electrical facsimile scanning signals in groups, all of the signals of each group effective as printing signals for a character, recording all transmitted signals upon a receiving strip in the form of characters, stopping the tape after each character recording at a uniform distance from the point of beginning of the facsimile character record, and causing a printing signal to start the tape.

18. A method of operating a facsimile telegraph system which comprises, sending electrical facsimile scanning signals in groups each group representing one character and all of the signals of each group representing printing signals of the character, recording all transmitted signals upon a receiving strip thereby recording upon the strip all of the transmitted characters, stopping the strip after each character recording at a uniform distance from the point of beginning of the facsimile character record, and causing the first received printing signal to print and to start the strip simultaneously.

19. In a telegraph receiver, facsimileing means comprising marker means and presser means, tape moving means, and control means for said tape moving means operable mechanically by said presser means.

20. In a facsimile telegraph receiver, facsimileing marker means, facsimileing presser means, tape moving means, and intermediate means controlling said tape moving means and controlled by said presser means.

21. In a facsimile telegraph receiver, facsimileing marker means, facsimileing presser means, tape moving means, and intermediate means controlling said tape moving means and controlled mechanically by said presser means.

22. In a facsimile telegraph receiver, facsimileing marker means, facsimileing presser means, motor driven tape moving means, and intermediate means normally restraining said tape moving means and controlled by said presser means to release said tape moving means for operation.

23. In a facsimile telegraph receiver, facsimile marking means, facsimile pressing means, motor driven tape moving means, restraining means for said tape moving means responsive to said pressing means and positioned in a zone of movement of said pressing means, and further means effective while said tape is being moved to reduce the movement of said restraining means.

CERTIFICATE OF CORRECTION.

Patent No. 2,145,264.

January 31, 1939.

EDWARD F. KLEINSCHMIDT.

It is hereby certified that error appears in the printed specification of the above numbered patent requiring correction as follows: Page 1, first column, line 40, for the word "type" read tape; line 41, for "charcter" read character; line 49, for "appaartus" read apparatus; page 3, first column, line 17, after the word "will" insert be; and that the said Letters Patent should be read with this correction therein that the same may conform to the record of the case in the Patent Office.

Signed and sealed this 6th day of June, A. D. 1939.

Henry Van Arsdale

(Seal)

Acting Commissioner of Patents.
